Specification for Design.

Patented Dec. 30, 1919.

Application filed June 13, 1919. Serial No. 304,064. Term of patent 14 years.

To all whom it may concern:

Be it known that I, JAMES E. RICH, a citizen of the United States, residing at Boston, in the county of Suffolk and State of Massachusetts, have invented a new, original, and ornamental Design for a Spark-Plug, of which the following is a specification, reference being had to the accompanying drawing, forming a part hereof.

Figure 1 is a side view of a spark plug, showing my new design.

Fig. 2 is an end view of the same.

I claim:

An ornamental design for a spark plug, as shown.

In testimony whereof I have affixed my signature.

JAMES E. RICH.
